UNITED STATES PATENT OFFICE.

HIRAM L. MELLOR, OF LAWRENCE, MASSACHUSETTS.

ROTARY PAPER-CUTTER.

SPECIFICATION forming part of Letters Patent No. 508,576, dated November 14, 1893.

Application filed April 15, 1893. Serial No. 470,462. (No model.)

To all whom it may concern:

Be it known that I, HIRAM L. MELLOR, of Lawrence, county of Essex, State of Massachusetts, have invented an Improvement in 5 Rotary Paper-Cutters, of which the following description, in connection with the accompanying drawings, is a specification, like letters and figures on the drawings representing like parts.

This invention relates to that class of paper cutting machines wherein the paper in web form is led through suitable feed rolls to a rotating feed drum, which delivers the web to fixed and movable cutting blades to be cut 15 thereby into sheets of desired length, the movable blade being mounted on a rotatable carrier which receives its motion from the feed drum through suitable intermediate mechanism, and my invention has for its object generally the simplifying of the various parts of the apparatus, and particularly the improvement of the mechanism connecting the feed drum and rotatable carrier.

In accordance therewith my invention consists, in a rotary paper cutter, of a rotatable cutter carrier, parallel actuating shafts geared respectively to said drum and carrier, and a friction surface rotatable with and longitudinally movable on each shaft, combined with 25 a double cone having a common base, said friction surfaces engaging the conical portions on opposite sides of their common base, and means to move the double cone longitudinally, whereby rotation of one friction 30 surface is transmitted to the other with varying speed, depending on the position of the double cone, substantially as will be described.

Other features of my invention will be hereinafter described and particularly pointed 35 out in the claims.

Figure 1, in side elevation and partly broken out, represents a rotary paper cutter with my invention applied thereto. Fig. 2 is a view 40 partly in section and broken out to save space, taken on the line $x-x$, Fig. 1, to be described, the cones and shafts being shown in elevation. Fig. 3 is a detail to be referred to; and Fig. 4 is a detail view in elevation, taken at 45 the left of Fig. 2, between the cone pulley P and bearing E^x .

The frame-work A of suitable shape to support the co-operating parts of the apparatus,

is provided with bearings a' and b' for the shafts a and b , of the feed drum B and cutter carrier C respectively, of usual construction, 55 and the feed-rolls B' , B' , guide B^2 , bracket B^3 supporting a presser-roll B^4 , delivering guide B^5 , and fixed and movable cutting blades c^x and c' are and may be of usual construction, 60 and form no part of my invention, suitable means being provided for adjusting the various parts.

The drum B has secured thereto a gear a^2 , see Fig. 1, in mesh with a gear a^3 , shown in dotted lines in Fig. 1, and in full lines Fig. 2, 65 fast on the rear end of a shaft E, best shown in Fig. 2, supported in suitable bearings secured to the frame-work A, said shaft having thereon a cone pulley P, connected by a belt P^2 with a reversed cone-pulley P' , on a shaft P^3 having its bearings p secured to the frame-work; and provided with usual fast and loose pulleys, not shown, rotation thereof being furnished from any suitable source of power. A shipper S is provided to move the belt P^2 70 from one to the other end of said cone pulleys in usual manner, to vary the speed of the driven pulley P, and thereby the speed of the drum. Heretofore it has been usual to vary the speed of the drum from speed changing mechanism outside of the machine, but by my construction herein described I obtain a more compact and simple apparatus, more convenient to operate, and easier to regulate.

The shaft E, see Figs. 2 and 4, at its front 85 end is provided with a sleeve e , rotatable therewith and longitudinally movable on the shaft in the bearing E^x , said sleeve having rigidly secured thereto outside of the bearing a disk or wheel E' with a recessed periphery, 90 to receive therein an endless friction surface or belt of suitable material, herein shown as an annulus E^2 , the face thereof being the frustum of a cone of small altitude and large base, said base or annulus being forced 95 onto the periphery of the wheel, whereby the same can be readily replaced when worn by a new one. Collars e' and e^2 , rigidly connected by a rod e^3 , loosely embrace the shaft E, the collar e' bearing against the end of the 100 sleeve e to move longitudinally therewith, but not to rotate. A flexible cord e^5 is attached at one end to the collar e^2 and passes over a sheave e^4 supported on the frame-work, and

thence to a lever e^6 , pivoted to the frame at 2, an adjustable weight w being movable longitudinally on the lever, as best shown in Fig. 3. The tendency of the weighted lever 5 and intermediate connections is to keep the sleeve e and friction surface E^2 pressed outwardly beyond the bearing F^x , for a purpose to be described.

The cutter carrier C has secured thereto a 10 gear b^2 , see Fig. 1, in mesh with a gear b^3 on the rear end of a shaft F, parallel to and independent of the shaft E, said shaft F having a longitudinally movable sleeve f keyed thereon to be rotated by it, said sleeve projecting 15 through the bearing F^x and having a wheel or disk F' fast thereon outside of said bearing, said disk carrying a frusto-conical annular friction surface F^2 , similar to the annulus E^2 . Collars f^1, f^2 , rigidly connected by 20 rod f^3 , and loose on shaft F, are acted upon by a flexible connection f^5 passed over a sheave f^4 and secured to a lever f^6 , said lever having an adjustable weight w' thereon, the action of said weight maintaining the collar 25 f' pressed against the end of the sleeve f , and tending to force it outwardly through the bearing F^x .

Brackets A', see Figs. 1 and 2, are secured to the frame-work, supporting bearings A² 30 and A³ for a shaft D', having a double cone D fast thereon, the cones having a common base, and inclining oppositely, as shown, the shaft D' being in the plane of the shafts E and F, and so located with relation to the friction surfaces E^2 and F^2 that they will simultaneously contact with the double cone D, on opposite sides of its greatest diameter or common base, the weights w and w' , keeping said friction surfaces always pressed 35 against the double cone. The shaft D' is longitudinally movable in its bearings, an externally threaded sleeve d' provided with a hand wheel d^3 being coupled to the shaft D' by a set nut d^2 entering an annular groove d in the shaft, so that the latter may rotate in the sleeve d' . The bearing A³ is internally threaded to engage the sleeve, and when the latter is rotated by the hand-wheel d^3 the shaft 40 and double cone D are moved in one or the other direction. By proper rotation of the sleeve the cone may be brought just intermediate the centers of the shafts E and F, and the friction surfaces E^2 and F^2 will then bear on conical portions of the same diameter, so that 45 if one surface be rotated at a given speed the other surface will be rotated at the same speed by or through the double cone. So, too, if the cone is so moved that the two surfaces contact with conical portions of different 50 diameters, as shown in Figs. 1 and 2, the driven surface will be rotated at a faster or slower speed than the driving surface. Consequently the speed of the driven surface may be varied with relation to the speed of the driving surface 55 simply by changing the position of the double cone.

The double cone D is substantially tangent

to the frusto conical friction surfaces E^2 and F^2 .

It will be remembered that the feed drum 70 B is geared directly to the shaft E, rotated by the speed changing pulleys P, and P', and the friction surface E^2 is positively driven by the rotation of said shaft. Therefore the cutter-carrier C, geared to the shaft F, which carries the friction surface F^2 , will be rotated by the power transmitted from the surface E^2 through the double cone D to the friction surface F^2 . Thus the speed of the cutter carrier 75 can be varied relatively to the speed of the feed drum, whether the latter is rotated at the highest or lowest speed, so that the length of the sheets to be cut from the web can be regulated with great nicety and precision, the conical friction surfaces greatly increasing 80 the accuracy and reliability of the mechanism, and the friction surfaces are constantly held against the double cone with a pressure which may be varied to suit the character of 85 the work.

This invention is not restricted to the specific construction of the various parts herein shown and described, as it is evident that the same may be somewhat altered, either in construction or arrangement, without departing 90 from the spirit of my invention.

I claim—

1. A feed drum, a rotatable cutter carrier, parallel actuating shafts geared respectively to said drum and carrier, and a friction surface rotatable with and longitudinally movable on each shaft, combined with a double cone having a common base, said friction surfaces engaging the conical portions on opposite sides of their common base, and means 100 to move the double cone longitudinally, whereby by rotation of one friction surface is transmitted to the other with varying speed, depending on the position of the double cone, substantially as described.

2. A rotatable feed-drum, a rotatable cutter carrier, independent parallel actuating shafts geared respectively to and to rotate said drum and carrier, a friction surface rotatable with and longitudinally movable on each shaft, and means to normally move said surfaces outwardly, combined with a double cone intermediate said surfaces and engaged thereby on opposite sides of its common base, and means to move the double cone longitudinally to present an increasing diameter to one, and a decreasing diameter to the other, of said friction surfaces, to vary the speed of the carrier with relation to the drum, substantially as described.

3. In a rotary paper cutter, a feed-drum, a power transmitting shaft geared thereto at one end and provided at its opposite end with a friction surface longitudinally movable thereon, a cutter-carrier, an actuating shaft therefor, and a friction surface longitudinally movable thereon, combined with a double cone in contact with and transmitting the rotation of one to the other of said friction sur-

faces, and means to move said cone longitudinally, whereby the speed of the cutter may be varied with relation to the speed of the drum, substantially as described.

5. 4. A drum actuating shaft, an independent carrier-actuating shaft, an annular friction surface rotatable with and longitudinally movable on each shaft, means to move said surfaces in one direction, combined with a shaft 10 located at right angles to said actuating shafts and movable longitudinally, a double cone thereon in contact with both and transmitting the rotation of one annular friction surface to the other, and means to move the cone 15 shaft longitudinally, movement of the central portion of the double cone toward a friction surface moving the latter inward upon its shaft, substantially as described.

5. In a rotary paper cutter, independent 20 drum and carrier actuating shafts, a frusto-conical friction surface rotatable with and longitudinally movable on each shaft, and driving mechanism for the drum actuating shaft, combined with a double cone, having a 25 common base, in engagement with said friction surfaces at opposite sides of said base, means to move the double cone to bring the base near one, and a conical apex near the other, of said surfaces, to vary the speed of 30 the driven frusto-conical surface with relation to the driving surface, substantially as described.

6. A feed drum, a rotatable cutter-carrier, independent actuating shafts geared thereto 35 respectively, a friction surface rotatable with and longitudinally movable on each shaft, and means for moving said surfaces in one direction with adjustable pressure, combined with a double cone having a common base

and in engagement with said friction surfaces on opposite sides of said base, and means to move the double cone longitudinally, the friction surfaces moving longitudinally on their shafts with or against the pressure applied to them as the cone is moved in one or 45 the other direction, substantially as described.

7. A feed drum, a rotatable cutter carrier, independent actuating shafts geared respectively to said drum and carrier, a removable friction surface rotatable with and longitudinally movable on each shaft, and a conical speed cone fixed to the drum actuating shaft, combined with a reverse cone connected therewith, a shipper therefor, to alter the speed of the driven cone, a double cone engaged by 55 said friction surfaces on opposite sides of its common base, and means to move said double cone longitudinally, whereby rotation of one surface is transmitted to the other with varying speed, substantially as described. 60

8. In a rotary paper cutter, independent actuating shafts, a wheel having a recessed periphery and a sleeve-like hub, rotated by and longitudinally movable on each shaft, and an annular belt or friction surface adapted to be forced onto the recessed periphery of each wheel, combined with a double cone engaged by each of said friction surfaces, to transmit power from one to the other, substantially as described. 70

In testimony whereof I have signed my name to this specification in the presence of two subscribing witnesses.
